TWISTING MACHINE FOR FLAT AND
FORMED BAR STOCK

Stanley J. Kopee, Detroit, Mich., assignor to The
Stanley Works, New Britain, Conn., a corpora-
tion of Connecticut

Application August 4, 1949, Serial No. 108,583

10 Claims. (Cl. 153—78)

1

This invention relates generally to a machine for twisting an elongated, flat piece of metal into an open helix and it relates more particularly to a machine for twisting a flat elongated length of bar stock in helical form for use in manufacturing a wood drill.

It has heretofore been a costly and time consuming process to form the fluting in a twist drill. It is necessary to utilize a comparatively large amount of stock in the manufacture of these drills which is wasted in the process of fluting them. Because prior processes of making wood drills have been complicated and time consuming, wood drills have been very high in cost and it has been practically impossible to supply the demand because of the low output of prior processes in manufacturing these drills.

It is, accordingly, an object of my invention to provide a machine for twisting flat bar stock, and particularly bar stock for use in wood drills, which is simple in construction, economical in cost, economical in manufacture, and efficient in operation.

Another object of my invention is to provide a machine for twisting flat bar stock which maintains the axial alignment of all parts of the twisted member after it passes from the machine.

Another object of my invention is to provide a novel die for a machine for twisting bar stock.

Another object of my invention is to provide a novel combination and arrangement of elements including electrical control means and hydraulic power means in a machine for twisting flat bar stock.

Other objects of my invention will become evident from the following detailed description, taken in conjunction with the accompanying drawings, in which

Fig. 1 is a plan view of my novel machine for twisting flat bar stock;

Fig. 2 is a side elevational view of one of the complementary parts of the die used in my novel machine for twisting flat bar stock;

Fig. 3 is a side elevational view of the novel die used in my machine for twisting flat bar stock;

Fig. 4 is an end view of the die shown in Fig. 3;

Fig. 5 is a view taken on the line 5—5 of Fig. 1 with my novel machine in a position to force a flat piece of bar stock through the die;

Fig. 6 is a view taken on the line 5—5 of Fig. 1 with my novel machine in a position whereby a flat piece of bar stock is ready to be disposed therein upon its movement towards a rear position;

Fig. 7 is a view taken on the line 7—7 of Fig. 6;

2

Fig. 8 is an end view taken from the end of my machine in which the die is located; and

Fig. 9 is a diagrammatical view of the hydraulic system for controlling the fluid to the hydraulic cylinder of my machine and electrical system used in conjunction therewith.

Referring now to the drawings, I show in Figs. 1, 5, and 6 a frame member 1 comprising vertically extending, parallel side frame members 2 and 3 secured to transverse base members 4 and 5. A spacing member 6 is disposed on one end of the side frame members 2 and 3 and secured thereto by screw bolts 7. Spacing member 8 is secured to the other end of the side frame members 2 and 3 by screw bolts 9, the member 8 having an axially extending aperture 10 with a counterbore 11 for receiving complementary dies 13 and 14 shown particularly in Figs. 2, 3, and 4. Dies 13 and 14 have recesses 15 for engaging locking screws 16a wherein they are locked in the counterbore 11 in the member 8. The dies 13 and 14 also have circumferentially spaced, longitudinally extending arcuate grooves 16 complementary to grooves 17 in the member 8 wherein longitudinally extending pins are disposed in the aligned grooves 16 and 17 to prevent rotation of the dies 13 and 14 relative to the counterbore 11 of the member 8. The dies 13 and 14 are each built so that when they are in an engaged complementary position as shown in Figs. 3 and 4, a helical aperture 18 extends the length of the dies 13 and 14 so that a flat bar of predetermined width and height will pass therethrough. The entrance to the helical groove 18 is shown in Fig. 4. Longitudinally extending, inwardly projecting members 21 and 22 are secured to the bottom and the top of the side frame members 2 and 3 to form guideways for a stationary base block 23 and a sliding clamp 24. The base block 23 is secured to the side frame members 2 and 3 by screw bolts 25 and it has a longitudinally extending groove 26 for receiving a hardened insert 27 with a longitudinally extending groove 28 with the upper portion thereof countergrooved at 29 for receiving a piece of bar stock to be pushed through the dies 13 and 14. The sliding clamp 24 slides on the base block 23 and it has a longitudinally extending groove 30 for receiving a hardened insert 31 with a longitudinally extending groove 32 complementary to the groove 28 in the insert 27 in the base block 23. The sliding clamp 24 locks the flat bar stock in the counter-grooves 29 of the groove 28. Complementary inserts 33 and 34 having rectangular recesses forming a cross slot 35 in alignment with the counter-

grooves 29 are disposed in the ends of the grooves 26 and 30 in the base block 23 and slide clamp 24 respectively. The rectangular cross slot 35 formed by the inserts 33 and 34 is substantially of the same cross sectional area of the bar stock to prevent it from buckling transversely and to steady the end thereof when it is being pushed through the dies 13 and 14. A push rod 36 having the same cross sectional shape as the complementary grooved portions 28 with counter grooves 29 in the insert 27 and groove 32 in the insert 31 respectively is slidably disposed in the grooves 28 and 32 between the base block 23 and slide clamp 24 and has one end thereof supported in a slideable supporting block 37, the end 38 thereof being threaded to threadably engage an adjustable locking collar 39 extending into an axially extending aperture 40 in the support block 37. The collar 39 has lock nuts threadably engageable therewith and a shaft 42 is secured to the member 39 and to a conventional piston (not shown) movable in a hydraulic cylinder 43 of conventional construction. The slide block 37 has an upwardly extending portion 44 upon which is pivotally mounted a finger latch 45 by a pin 46, one end of the latch 45 having a hooked portion 47 for engaging a latch block 48 on the slide clamp 24. A coil spring 49 urges the hooked end 47 of the latch 45 downwardly so that it automatically engages the latch block 48 when it is moved to a position wherein the block 37 engages the slide clamp 24 as shown in Fig. 6. The latch block 48 has a contact member 50 with forwardly and rearwardly projecting contact points 50a and 50b secured to the side thereof for engaging microswitches 52 and 53 on opposite ends of the stroke of the slide clamp 24. The relation of these switches 52 and 53 with the hydraulic system and the electrical control system therefor will be hereinafter described.

The hydraulic cylinder 43 has pipe lines 54 and 55 in fluid flow relationship with opposite ends thereof as shown diagrammatically in Fig. 9. The lines 54 and 55 are in fluid flow relationship with a solenoid operated valve 56 having a slideable piston 60a with three reduced portions 57, 58, and 59 forming chambers adapted to direct the flow of fluid from the fluid line 60 to the fluid lines 54 and 55 alternately to cause the movement of the piston in the power cylinder 43. A fluid line 62 leading from the valve 56 is in fluid flow relationship with a reservoir or tank 63 to provide for the return of fluid from one or the other of the lines 54 and 55 alternately. Solenoids 64 and 65 move the piston 60a longitudinally to alternate positions. The solenoid 65 is connected to the power lines 66 and 67 through wire 68, wire 70, switch 52, solenoid 65, and wires 74 and 72 to the power line 66. The solenoid 64 obtains its power from the power lines 66 and 67 through the wire 68 and switch 69, wire 73, solenoid 64, wire 74, and wire 72 back to the power line 66. The wire 73 also has connected thereto wire 76 which is connected to solenoid 77 of solenoid operated valve 78, and wire 79 back to the power line 66. The valve 78 also has a solenoid 80 on the opposite end thereof connected to power lines 66 and 67 through a microswitch 53, wire 82, solenoid 80, and wire 83 back to the power line 66. The valve 78 has pistons 84 and 85 for alternately closing the line 86 leading to the tank 63 and the line 60 leading to the valve 56. The valve 78 has fluid lines 87 and 89 leading therefrom in fluid flow relationship with a pump 88 and the tank 63 respectively. A conventional electric

motor 90 is connected to the pump 88 by a shaft 91 and coupling 92. The microswitch 52 is provided in the circuit to energize the solenoid 64 after the piston in the cylinder 43 moves to the left in its power stroke thereby causing the return of the piston and sliding member 24 to their original positions.

In the operation of my novel machine for twisting flat bar stock, the slide member 24 is moved to its rearwardmost position with the contact member 50a in engagement with the microswitch 53 thereby closing the circuit made by wires 67 and 68, switch 69, wire 81, wire 82, solenoid 80, and wire 83 to the power line 66 to energize the solenoid 80 and cause the fluid under pressure caused by the operation of the motor 90 and pump 88 to flow through the fluid line 86 back into the tank 63 and return through the fluid line 89. A piece of flat bar stock is then laid in the counter grooves 29 in the base member 23 and the slide clamp 24 is pushed forwardly into engagement with the member 8 thereby locking the bar stock in the counter grooves 29 of the base member 23. The switch 69 is then energized causing the energization of the solenoids 77 and 64 of the valves 78 and 56 respectively thereby placing the line 60 leading to the valve 56 in fluid flow relationship with the line 87 leading from the pump 88 and the line 60 is placed in fluid flow relationship with the fluid line 55 leading to the right end of the cylinder 43 causing the piston therein to move towards the left end thereof. When the valve 56 is pulled in the opposite direction by the solenoid 65, the line 54 is in fluid flow relationship with the return line 62 leading to the tank 63. As the piston in the cylinder 43 moves to the left, the plunger 36 will engage the end of the bar stock and force it through the groove 48 in the dies 13 and 14 wherein it will emanate from the outer end thereof in twisted form as shown in Fig. 5. After the supporting block 37 moves to a position in engagement with the block 23 and sliding clamp 24, the contact member 50b of the member 50 engages the microswitch 52 thereby moving the piston 60a in the valve 56 to the left and placing the line 60 in fluid flow relationship with the line 54 to cause the piston in the cylinder 43 to move to the right and thereby moving the supporting block 37, plunger 36, and slideable member 24 to the right. The hooked portion 47 of the latch 45 engages the latch block 48 so that the slide member 24 is drawn to the rear with the support member 37. When the support member 37 moves to the right to the completion of its stroke, contact member 50a engages the microswitch 53 thereby energizing the solenoid 80 to place the pipe line 87 in fluid flow relationship with the return line 86 to the tank 63.

When a flat piece of bar stock is twisted by my machine, it is only necessary to weld a shank on one end thereof and a threaded nose on the other end thereof by any well known welding method to form a wood drill. These wood drills have been found to be very satisfactory in operation and they can be made at a cost of much less than half of any of the cost of making the prior fluted wood drills.

Although I have shown and described a machine for twisting flat bar stock, it will be evident that my machine may be utilized for twisting bar stock having the central part thereof thicker than the lateral outer sides thereof. The stock may converge laterally outwardly from the center thereof or the central portion thereof may be rounded or arcuate in shape.

It will be evident from the foregoing description that I have provided a novel machine for twisting flat bar stock into open helical form which automatically performs the twisting of the rod after it is placed in a locked position and a switch is actuated, one which has automatic return means for the plunger, one which has automatic means for bypassing the hydraulic fluid back to the tank when my machine is not in operation, one which has novel dies and a novel combination and assembly of parts to prevent misalignment of the bar when it is being twisted and automatic means for holding the bar stock in a position wherein it may be slid longitudinally without misalignment and twisted.

Various changes may be made in the specific embodiment of my invention without departing from the spirit thereof or from the scope of the appended claims.

What I claim is:

1. A machine for twisting flat bar stock comprising a stationary member having a longitudinally extending groove for receiving a piece of flat bar stock, a complementary slideable guide member longitudinally movable over said groove on said stationary member to cover the bar stock in said groove in said member, said groove in said stationary member being exposed when said slideable member is moved therefrom to receive a piece of bar stock, a die in alignment with said groove in said stationary member having an internal, helically extending aperture, a push rod for forcing said bar stock longitudinally through the aperture in said die and out of the groove in said stationary member, and power means for moving said push rod.

2. A machine for twisting flat bar stock comprising a frame, a stationary support block mounted on the frame having a longitudinally extending T-shaped groove in one surface thereof adapted to receive a piece of flat bar stock, a die mounted on the frame having a helically extending aperture extending axially thereof in alignment with the groove in said support block, a guiding member having a surface adapted to cover the groove in the support block, means whereby the guiding member is retained in superposed position on the support block to hold a piece of work in said T-shaped groove but permitted to slide to a position exposing the groove for the insertion of a piece of work therein, a push rod movable in the groove in said support block for pushing said bar stock through said helical aperture in said die, and means for moving said push rod.

3. A machine as set forth in claim 2 wherein the means for moving said push rod comprises a shaft, an hydraulic cylinder, a piston movable in said cylinder connected to said shaft, and means for alternately admitting fluid to opposite ends of said hydraulic cylinder.

4. A machine as set forth in claim 2 wherein a spring urged finger is movable with said push rod to engage said guide member to move it longitudinally on said support block.

5. A machine as set forth in claim 2 wherein said guide member has a contact member movable therewith, microswitches are disposed adjacent

the ultimate forward and return movement position of said guide member, means are connected to the switch adjacent said guide member in its forward position engageable by said contact for reversing the flow of fluid to said hydraulic cylinder, and means are connected to said switch adjacent said guide member in its return position to direct fluid away from said cylinder.

6. A machine for twisting flat bar stock comprising a frame, a stationary support block in said frame having a longitudinally extending groove with center grooved portions on each side thereof adapted to receive a piece of flat bar stock, a guide block adapted to cover the groove in the support block, holding means cooperating with the support block whereby the guide block may be slid from superposed position on the support block to retain a piece of work in said groove and a position exposing the groove for the insertion of a piece of work therein, a die having a longitudinally extending helical aperture for receiving said bar stock in alignment with the counter-grooves in said support block, a push rod for pushing said bar stock through the aperture in said die, hydraulic means for reciprocating said push rod, and means for controlling the hydraulic fluid.

7. A machine as set forth in claim 6 wherein said hydraulic means comprises an hydraulic cylinder having supports on opposite ends thereof, a piston therein, a shaft connected to said piston and to said push rod, fluid under pressure for admission to opposite ends of said hydraulic cylinder, and means for controlling said fluid under pressure to alternately admit and exhaust fluid from opposite ends of said cylinder progressively.

8. A machine as set forth in claim 7 wherein solenoid valves are provided for controlling the fluid admitted and exhausted from said hydraulic cylinder, solenoids for operating said solenoid valves, a source of power for actuating said solenoids, and switch means for controlling said solenoids.

9. A machine as set forth in claim 8 wherein said guide member has a contact member movable therewith to engage a microswitch on the forward movement thereof which is electrically connected to one of the solenoids controlling a solenoid controlled valve to reverse the flow of fluid passing to and from said hydraulic cylinder.

10. A machine as set forth in claim 6 wherein said stationary support block and said guide member have complementary recesses on the ends thereof adjacent said die to receive hardened inserts defining an oblong aperture substantially the size of the bar stock passing therethrough to said die.

STANLEY J. KOPEC.
